CLAIM

The ornamental design for a rapid ops shelter, as shown and described.

DESCRIPTION

FIG. 1 is a top-front-left perspective view of a rapid ops shelter showing my new design;

FIG. 2 is a detailed view of section 2 of FIG. 1;

FIG. 3 is a bottom-front-right perspective view thereof;

FIG. 4 is a detailed view of section 4 of FIG. 3;

FIG. 5 is a front elevational view thereof;

FIG. 6 is a detailed view of section 6 of FIG. 5;

FIG. 7 is a rear elevational view thereof;

FIG. 8 is a top plan view thereof;

FIG. 9 is a bottom plan view thereof;

FIG. 10 is a left side elevational view thereof; and,

FIG. 11 is a right-side elevational view thereof.

1 Claim, 11 Drawing Sheets
